(57) **CLAIM**

The ornamental design for an open ratchet handle, as shown and described.

DESCRIPTION

FIG. 1 is a perspective view of an open ratchet handle showing my new design;

FIG. 2 is a front end view thereof;

FIG. 3 is a rear end view thereof;

FIG. 4 is a side view thereof;

FIG. 5 is an opposing side view thereof;

FIG. 6 is a top view thereof;

FIG. 7 is a bottom view thereof;

FIG. 8 is a front end view of an enlarged open ratchet handle without any environmental structure thereof;

FIG. 9 is a rear end view thereof;

FIG. 10 is a side view thereof;

FIG. 11 is an opposing side view thereof;

FIG. 12 is a bottom view thereof; and,

FIG. 13 is a top view thereof.

The broken lines illustrated in FIGS. 1-7, 9 and 13 represent environmental structure, which is not considered a part of the claimed design.
